(54) **BUTTONS, SECURING IN A LATHE**

(76) Inventor: **George W. Robinson**

The schedule referred to in the Letter Patent and making part of the same, containing a description in the words of the said George W. Robinson himself of his mode of securing a bullet in a chock for turning by two springs.

The springs are firmly attached to the chock or stock piece, which is secured to the handill at the end of the spring piece, so that when they are fastened to the chock, is a shoulder on each spring projecting inward, which shoulder has an impression made in it to receive a wedge. At the distance back of these shoulders are two other shoulders, one projecting both of them together and those on the end of the springs, that bear into a mortise made in the chock or stock piece and nail or a nail in the middle with a head like a thumb nail, is placed in the centre between the two springs in the stock. The nail when turned one way bears upon the second described shoulder or projection on one spring piece, the spring apart ready to receive the eye of a bullet.

The eye of the bullet is put thro' a small orifice made in the end of a chock or stock piece large enough to receive it, then the nail and being turned back so that it lies flat ways with the springs, the spring forced downward closing the two first described shoulders and fastened in this way, with the nail of the sort of wedge, holding the bullet firm to the surface of the stock or stock piece which occurs, the bullet fast in the latter following.
